UNITED STATES PATENT OFFICE.

GEORGE W. PIGGOTT, OF NEW YORK, N. Y., ASSIGNOR TO ALEXANDER CROW AND ALEXANDER CROW, JR., BOTH OF PHILADELPHIA; PA.

DESIGN FOR A CARPET.

SPECIFICATION forming part of Design No. 14,342, dated October 2, 1883.

Application filed August 6, 1883. Term of patent 3½ years.

To all whom it may concern:

Be it known that I, GEORGE W. PIGGOTT, of New York, in the county and State of New York, have invented and produced a new and original Design for a Carpet, of which the following is a full description, in connection with the accompanying photograph, which represents a face view of my new design for a carpet.

This invention relates to a new configuration of ornaments on the face of a carpet or analogous fabric.

In the photograph, the letter A represents the central floral decoration of the carpet, which is a bouquet placed upon the background, said background showing in faint

tints or shades a series of leaves and flowers, upon which the bouquet A seems to have been thrown, and on which also appear bouquets B, C, and D of peculiar outline, all as indicated in the photograph. The figures on the background are indicated by the letter E.

I claim—

The design for a carpet, the same consisting of the figures A B C D E, substantially as shown.

GEORGE W. PIGGOTT.
